UNITED STATES PATENT OFFICE.

LESLIE ANTHELM SCHOEN, OF VICTOR, COLORADO.

DESIGN FOR A PATRIOTIC BADGE OR POSTER.

51,764.

Specification for Design.

Patented Feb. 12, 1918.

Application filed November 16, 1917. Serial No. 202,415. Term of patent 3½ years.

To all whom it may concern:

Be it known that I, LESLIE ANTHELM SCHOEN, a citizen of the United States, residing at Victor, in the county of Teller and State of Colorado, have invented a new, original, and ornamental Design for a Patriotic Badge or Poster, of which the following is a specification, reference being had to the accompanying drawing, forming part thereof.

The figure is a front view of a patriotic badge or poster showing my new design.

I claim:

The ornamental design for a patriotic badge or poster, as shown.

LESLIE ANTHELM SCHOEN.
